JULIUS RITTER, JR., AND MARIUS J. WISBY, OF RACINE, WISCONSIN, ASSIGNEES TO
HARTMANN TRUNK COMPANY, OF RACINE, WISCONSIN, A CORPORATION OF WIS-
CONSIN.

DRAWER-LOCKING DEVICE.

Application filed December 10, 1926. Serial No. 153,810.

This invention relates to improvements in trunk drawer locking devices.

Wardrobe trunks are usually formed in two sections, and one of said sections is commonly provided with a drawer section in which a plurality of drawers are positioned, one above the other. If no provision is made for locking the drawers, they will slide back and forth and not maintain their position during transportation, and injure the contents.

It is, therefore, the primary object of the present invention to provide, in a drawer equipped trunk, an improved means for locking all of the drawers in a series.

A further object of the invention is to provide a trunk drawer locking device in which the majority of the drawers in a series are locked by a locking member, and the remaining drawer is locked by an independent lock, the locking of the remaining drawer serving to prevent access to the locking means for other drawers.

A further object of the invention is to provide, in a drawer equipped trunk, a locking means for some of the drawers which is hidden and is not readily apparent to anyone tampering with the trunk.

A further object of the invention is to provide a trunk drawer locking device which is of very simple construction, is easy and efficient in operation, is strong and durable, and is well adapted for the purpose described.

With the above and other objects in view, the invention consists of the improved trunk drawer locking device, and its parts and combinations as set forth in the claims, and all equivalents thereof.

In the accompanying drawing in which the same reference characters indicate the same parts in all of the views:

Fig. 1 is a front view of the drawer section of a trunk, the two upper drawers being removed;

Fig. 2 is a vertical sectional view of the drawer section taken on line 2—2 of Fig. 1;

Fig. 3 is an enlarged fragmentary view taken on line 3—3 of Fig. 4 showing the locking means for some of the drawers;

Fig. 4 is an enlarged fragmentary vertical sectional view showing the locking means and a drawer engaged thereby;

Fig. 5 is a fragmentary cross-sectional view

through the drawer section and a plan view 55 of a drawer therein showing the locking means for said drawer; and

Fig. 6 is a sectional view taken on line 6—6 of Fig. 1, and on a larger scale.

Referring now more particularly to the drawings it will appear that the numeral 8 indicates the drawer section of a wardrobe trunk which is provided with a plurality of drawers 9 positioned one above the other and slidably supported upon angled strips 10 65 mounted on opposite sides of the trunk section. The upper drawer 9' is preferably provided with a lock 11 and a key 12 controlling the same.

A plurality of brackets 13 are mounted 70 medially in a vertical line on the rear inner surface of said trunk section, and extending through said brackets is a vertically movable bar 14. Secured to the bar 14 at proper intervals are angular fingers 15 which are 75 formed with ribbed off-set portions 15', as best shown in Fig. 6.

Pivotedly connected to the upper portion of the bar 14 is a short link 16 which has pivotally connected thereto a second short 80 link 17. A bracket 13' is secured to the rear of the trunk section over said link 17 and the inner end portion of a lever 18 is mounted in said bracket and is secured to said link 17 to actuate the same. Said lever 18 extends 85 at right angles to the bar and links and is revolvably mounted at its outer end portion in a support 19 depending from a strip 20 secured to opposite sides of the trunk section. The lever 18, outwardly of the support 19, 90 is bent at an angle to form a handle.

Each of the drawers 9 has secured to the lower portion of its rear wall, an outwardly projecting complementary lock member or bracket 21 which is downwardly and inwardly tapered, as shown in Fig. 6. Said brackets are arranged so as to be immediately below and in register with the brackets 13 when the drawers are pushed to their innermost positions.

In use, the drawers 9 are pushed to their inner positions and the angular handle portion of the lever 18 is turned to the position shown in Figs. 1 and 5 and motion will be transmitted thereby through the links 16 and 17 to the bar 14, dropping the same to its lowermost position. In this position, the fingers 15 carried thereby will move down-

wardly through the brackets 13 and enter the drawer brackets 21, as shown in Figs. 3, 4 and 6. Due to the taper of the drawer brackets 21 and the off-set portions 15' of the 5 fingers, the fingers, on entering the brackets 21, will cause a wedging or drawing action, to force and firmly hold the drawers in their inner positions. Also, the position of the brackets 13, immediately above the brackets 10 21, relieves the latter, as well as the fingers 15, from undue strain. With the lever 18 in the position indicated and described, the top drawer 9' may then be inserted and the same covers, conceals and prevents access to 15 said lever. The top drawer is locked by means of the lock 11 and key 12, and when so locked the drawers 9 therebelow cannot, of course, be unlocked and opened. Even though the upper drawer be unlocked, the 20 locking mechanism for the other drawers is hidden, and a person unfamiliar with the trunk mechanism cannot readily open said drawers.

From the foregoing description it will be 25 seen that the improved trunk drawer locking mechanism is of very simple and novel construction, and is well adapted for the purpose described.

What is claimed as the invention is:

30 1. The combination with a trunk section having a plurality of drawers positioned one above the other, some of the drawers being formed at their rear ends with complementary locking members, of a locking means 35 for said drawers, comprising a lock for one of the drawers, a bar slidably mounted on the inner surface of the rear of the trunk section and having fingers which lockingly engage the complementary locking members 40 of the drawers so equipped, and a lever extending from said bar below said lock equipped drawer forwardly to the front edge of said drawer and movable to unlock said other drawers only when the lock equipped 45 drawer is withdrawn from the trunk section.

2. The combination with a trunk section having a plurality of drawers positioned one above the other, of a locking means therefor, comprising a lock for the upper drawer, 50 downwardly and inwardly tapered brackets secured to the rear portions of the lower drawers, a bar mounted on the inner surface

of the rear of the trunk section and having intermediate fingers which enter said brackets to lock said drawers in closed position, the bar being longitudinally movable, links 55 pivotally connected to said bar, and an operating lever secured to and projecting forwardly from one of the links beneath the lock equipped upper drawer and operable to 60 move the bar and fingers to unlocking position only upon the withdrawal of the lock equipped drawer.

3. The combination with a trunk section having a plurality of drawers positioned one 65 above the other, of a locking means therefor, comprising a lock for the upper drawer, downwardly and inwardly tapered brackets secured to the rear portions of the lower 70 drawers, a bar mounted in brackets on the inner surface of the rear of the trunk section and having intermediate fingers formed with offset wedging portions which enter said drawer brackets to lock said drawers in closed position, the bar being vertically mov- 75 able, a pair of pivotally connected links pivotally connected to the upper portion of the bar, and an operating lever secured to and projecting forward from one of the links and underlying the upper drawer, said lever hav- 80 ing an angular end portion movable to a position wherein the bar is raised and the fingers disengaged from the drawer brackets only upon the withdrawal of the upper drawer from the trunk section.

4. The combination with a trunk section having a plurality of drawers positioned one 85 above the other, of a locking means therefor, comprising a lock for the upper drawer, downwardly and inwardly tapered brackets 90 secured to the rear portions of the lower drawers, a bar mounted in brackets on the inner surface of the rear of the trunk section and having intermediate fingers formed with offset wedging portions which enter said 95 drawer brackets to lock said drawers in closed position, the bar being vertically mov- able, and an operating lever projecting forwardly from said bar beneath the lock equipped drawer.

In testimony whereof, we affix our signatures.

JULIUS RITTER, Jr.
MARIUS J. WISBY.
